UNITED STATES PATENT OFFICE.

HARRY AGLOW, OF NEW YORK, N. Y., ASSIGNOR TO ARTCRAFT METAL STAMPING CORPORATION, OF BROOKLYN, NEW YORK, A CORPORATION OF NEW YORK.

DESIGN FOR A CHANDELIER.

Application filed November 19, 1923. Serial No. 7,820. Term of patent 3½ years.

To all whom it may concern:

Be it known that I, HARRY AGLOW, subject of British Empire, and residing at 1077 Boston Road, New York city, in the county of New York and State of New York, have invented a new, original, and ornamental Design for Chandelier, of which the following is a specification, reference being had to the accompanying drawing, forming part thereof.

The figure shows a side elevation of my design for an electric chandelier.

I claim:

The ornamental design for a chandelier as shown.

HARRY AGLOW.
